UNITED STATES PATENT OFFICE.

BAYARD A. BERRYMAN AND ALANSON B. WAKEFIELD, OF ST. LOUIS, MO.

IMPROVEMENT IN HOSE-PIPE NOZZLES.

Specification forming part of Letters Patent No. **137,881**, dated April 15, 1873; application filed March 17, 1873.

To all whom it may concern:

Be it known that we, BAYARD A. BERRYMAN and ALANSON B. WAKEFIELD, of the city and county of St. Louis and State of Missouri, have invented a certain Improvement in Nozzles for Hose-Pipes, of which the following is a specification:

Our invention consists in rifling or forming spiral creases in the interior of a hose-nozzle, and screwing upon the outer end a smooth-bore tip, the purpose of this construction being to impart a rotary motion to the water passing through the nozzle, which enables the water to be forced in a solid body from the nozzle without becoming broken or spraying; the object of the smooth-bore tip being to collect the water and cause it to be discharged in a cylindrical body. Our invention also relates to forming an enlargement or chamber between the grooved and smooth parts of the nozzle, in which the water rotates before it enters the smooth-bore tip.

Figure 1 is a longitudinal axial section. Fig. 2 is a transverse section of the smooth-bore tip at line *x x*. Fig. 3 is a transverse section of the rifled portion of the nozzle at line *y y*.

A is the barrel of the nozzle of any suitable

form and degree of taper. The barrel is formed with a number, two or more, of spiral creases, *a*, extending forward to the chamber *B*. The interior of the tip *C* is made tapering and smooth, and is preferably made to screw upon the part *A*, and a gasket, *e*, being interposed at the union of the two parts to prevent leakage. The barrel *A* is recessed at *B* to form an annular chamber, in which the water has free rotation, and from which it enters the smooth-bore tip *C* in a solid body having rotary motion.

What we claim is—

1. The barrel *A* formed with spiral creases *a*, as and for the purpose set forth.
2. The barrel *A* having spiral creases *a*, in combination with the smooth-bore tip *C*, as and for the purpose set forth.
3. The combination and arrangement of the barrel *A*, spiral creases *a*, and tip *C* with the chamber *B*, as and for the purpose set forth.

BAYARD A. BERRYMAN,
ALANSON B. WAKEFIELD.
